REEL

Filed Aug. 21, 1929

H. H. Bensema.

INVENTOR.

BY *Lacey Lacey*,
ATTORNEY.

UNITED STATES PATENT OFFICE

HARM H. BENSEMA, OF GILMAN, ILLINOIS

REEL

Application filed August 21, 1929. Serial No. 387,440.

The present invention is directed to improvements in reels.

The primary object of the invention is to provide a reel more particularly designed for use in connection with barbed wire but it is not necessarily limited to such use as other material can be conveniently reeled thereon.

Another object of the invention is to provide a reel so constructed that it can be easily 10 and quickly applied to the coiled wire and removed therefrom as desired.

Another object of the invention is to provide a device of this character which, when in use, will hold the coiled wire firmly against 15 slippage so that the reeled coil will remain uniform and can be conveniently and evenly unreeled when desired.

With these and other objects in view, this 20 invention resides in the novel features of construction, formation, combination and arrangement of parts to be hereinafter more fully described, claimed and illustrated in the accompanying drawing, in which:

Figure 1 is a perspective view of the 25 device.

Figure 2 is a sectional view on the line 2—2 of Figure 1.

The reel comprises a pair of bars 1 and 2, 30 said bars being secured at their inner overlapped sections by a clamping bolt 3, said bolt serving to not only secure the bars in rigid relation but will permit disengagement thereof when it is desired to fold or disassemble the reel. Since the bars 1 and 2 are identical in 35 shape and form, the description of one will suffice for both.

To the end of one bar is riveted or otherwise secured a fork 4, said bar being partially twisted as at 5 so as to properly position the fork with respect to the associated fork. To the other end of the bar is fitted a slide 6, said slide having bolted thereto the inner end of the screw shaft 7, said shaft being passable through an opening 8 formed 40 in the inturned flange 9 carried upon the terminal of the bar. Encircling the screw shaft 7 is a coil spring 10, the outer end of which bears against the flange 9, while the inner end thereof bears against the slide 6, said spring 45 tending to slide the slide 6 inwardly upon its

associated bar, the purpose of which will later appear. The screw shaft 9 has a fork 11 fixed to its outer end for cooperation with the forks 4 in order that the wire can be conveniently reeled or coiled around the device 55 and maintained in proper position. The screw shaft 7 has mounted thereon a wheel having threaded engagement therewith, said wheel bearing against the flange 9, and, obviously, when the wheel is rotated in one direction the screw shaft 7 will be fed outwardly and when rotated in a reverse direction the spring 10 will serve to slide the screw shaft 7 inwardly so that the fork 11 associated therewith can be adjusted so that the reel can 60 be removed from the reeled or coiled wire. 65

After the wire has been reeled or coiled upon the device and it is desired to remove the entire coil, it is only necessary to rotate the wheel 12 inwardly to cause inward movement of the screw shaft 7, whereupon the fork 11 thereof will move to a position to permit 70 convenient removal of the reel from the coil and, obviously, the operation is reversed when it is desired to insert the reel in a coil of 75 wire.

From the foregoing, it is thought that the 80 operation and many advantages of the herein described invention will be apparent to those skilled in the art without further description and it will be understood that various changes in size, shape, proportion and minor details of construction may be resorted to without departing from the spirit or sacrificing any 85 of the advantages of the invention. 85

What is claimed is:

1. A device of the class described comprising a pair of fixed cross bars having forks rigidly connected to one of their ends, slides carried by the other ends of the bars, said other ends having flanges provided with openings, screw shafts having one of their ends fixed with the slides and movable in said openings, springs encircling the shafts and interposed between the slides and flanges, 90 hand wheels threaded upon the shafts and bearing upon the flanges, and forks carried by said screw shafts. 95

2. A reel comprising an arm having a 100 terminal lateral extension in which is formed

an opening, a slide freely movable on the arm, a screw at one side of the arm passing through the opening of the lateral extension and connected at its inner end to the slide, a coil spring on the screw confined between the slide and lateral extension and normally urging the slide and screw inwardly, a wheel threaded on the screw and in contact with the outer side of said lateral extension and a supporting member at the outer end of the screw and adjustable therewith.

3. A reel comprising crossing bars having one end flanged and formed with an opening, a fork at the opposite end, a slide on the flanged end, a screw mounted in the flange and secured to the slide, a coil spring on the screw confined between the flange and slide, a wheel threaded on the screw and engaging the outer side of the flange, and a fork at the outer end of the screw.

4. A reel comprising crossed bars having a flange at one end in which is formed an opening, a bolt connecting the bars at the point of crossing, a fork at the opposite end of the bars, slides on the flanged ends of the bars, screws mounted in the flanges and connected at their inner ends to the slides, coil springs on the screws confined between the flanges and slides, forks at the outer ends of the screws, and wheels threaded on the screws and engaging the outer sides of the flanges.

In testimony whereof I affix my signature.
